CLAIM

The ornamental design for a hobby horse, as shown and described.

DESCRIPTION

FIG. 1 is a left side view of a hobby horse showing my new design and wherein a right side view is a mirror image thereof;

FIG. 2 is a rear elevational view thereof;

FIG. 3 is front elevational view thereof;

FIG. 4 is a bottom perspective view thereof;

FIG. 5 is a front perspective view thereof;

FIG. 6 is a side elevational view of a modified embodiment of the design shown in FIGS. 1-5;

FIG. 7 is a front elevational view thereof;

FIG. 8 is a rear elevational view thereof;

FIG. 9 is a bottom perspective view thereof; and,

FIG. 10 is a front perspective view thereof.
